(57) **CLAIM**

The ornamental design for a control knob, as shown and described.

DESCRIPTION

FIG. 1 is a first perspective view of the control knob showing a first embodiment of my new design;

FIG. 2 is a second perspective view thereof;

FIG. 3 is a front elevation thereof;

FIG. 4 is a back elevation thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a cross-sectional plan view at section line 9-9 in FIG. 5;

FIG. 10 is a cut-away perspective view of FIG. 9;

FIG. 11 is a first perspective view of the control knob showing another embodiment of my new design;

FIG. 12 is a second perspective view thereof;

FIG. 13 is a front elevation thereof;

FIG. 14 is a back elevation thereof;

FIG. 15 is a left side elevation view thereof;

FIG. 16 is a right side elevation view thereof;

FIG. 17 is a top plan view thereof;
